JOHN WALDHEIM, OF NEWARK, NEW JERSEY, ASSIGNOR, BY MESNE ASSIGNMENTS,
TO REMINGTON TYPEWRITER COMPANY, OF ILION, NEW YORK, A CORPORATION OF
NEW YORK.

TABULATING MECHANISM FOR TYPE-WRITERS AND COMPUTING-MACHINES.

1,177,909.

Specification of Letters Patent.

Patented Apr. 4, 1916.

Application filed February 1, 1912. Serial No. 674,718.

To all whom it may concern:

Be it known that I, JOHN WALDHEIM, a citizen of the United States, and resident of Newark, in the county of Essex and State 5 of New Jersey, have invented certain new and useful Improvements in Tabulating Mechanism for Type-Writers and Computing-Machines, of which the following is a specification.

- 10 My invention relates to typewriting machines and computing machines and it has for its principal object to provide improved tabulator mechanism for positioning a carriage.
15 I have provided tabulator mechanism for arresting the carriage of the typewriter and of the computer in any desired denominational position in any one of a plurality of columns. One of the features of novelty of
20 this tabulator mechanism resides in the fact that I provide both column keys and denominational keys and denominational stops, and the construction is such that when any denominational key is operated the carriage
25 will be arrested in the corresponding denominational position by the first column stop to reach the operated denominational stop; but if one of said column keys be first operated and then a denominational key is
30 operated, the operation of the column key renders the denominational stops incapable of arresting any other column stop than the one corresponding to the operated column key.
35 To the above and other ends which will hereinafter appear, my invention consists in certain features of constructions, and combinations and arrangements of parts, all of which will be fully set forth herein and
40 particularly pointed out in the claims.

One embodiment of my invention is illustrated in the accompanying drawings in which—

Figure 1 is a side elevation of so much of
45 a combined typewriting and computing machine as is necessary to illustrate the embodiment of my invention therein. Fig. 2 is a plan view of the forward part of said machine. Fig. 3 is a skeleton view similar

to a part of Fig. 1 but showing a denominational tabulator key operated without operating a column key. Fig. 4 is a view similar to the upper part of Fig. 3 but showing the positions of the parts when a column key is operated but no denominational key 55 is operated. Fig. 5 is a view similar to Fig. 4 with the column key operated and with a denominational stop also operated. Fig. 6 is a side view of one of the adding heads and showing the latch or detent in released 60 position. Fig. 7 is a left-hand side elevation of a tabulator stop device arranged to be mounted on the computer carriage but not associated with or constituting part of an adding head. Fig. 8 is a fragmentary 65 rear elevation of the denominational stops and some of the associated parts.

All of the figures of the drawing are on a reduced scale and in all of them parts have been shown in section or broken away 70 or omitted entirely as has been found convenient.

I have shown my invention applied to a Wahl adding machine mounted as an attachment on a Remington No. 11 typewriter. It 75 will, of course, be understood that the invention can be applied or adapted to other combined typewriting and computing machines, and some of its features are applicable to other than combined machines. 80

The main frame of the Remington typewriter comprises a base 1, corner posts 2 and a top plate 3. Stationary rails 4 support, by means of roller bearings, a carriage truck 5 which has a shift frame 6 mounted 85 therein by means of links 7 which allow said shift frame to be moved up and down to a limited extent for upper and lower case writing. A platen 8 has its axle 9 journaled in said shift frame. The means 90 for shifting this frame are not shown herein.

The carriage is fed across the machine toward the left by a strap 10 running over a spring drum 11 and connected to said carriage. The feed of the carriage is controlled by means which include a feed rack 12 which is pivoted to the truck 5 at 13 and which en-

gages a feed pinion 14, the shaft of which is journaled in a bracket 15 and at its rear end carries two escapement wheels 16. Said escapement wheels are controlled by a feed 5 dog mounted on the upper end of an arm 17 of a dog rocker, which dog rocker is pivoted at 18 to a bracket of the main frame. Said dog rocker has another arm 19 which is connected by a link 20 with an arm 21 projecting 10 toward the rear from a rock shaft 22 (Figs. 2 and 3). Said rock shaft is pivoted at 23 in the base 1 on pivot screws and it has at the ends thereof arms 24 projecting toward the rear and supporting, by means of 15 depending links 25, the universal bar 26 of the typewriter. Said universal bar lies beneath the series of printing key levers 27 which at their forward ends bear keys 28. These keys are arranged in rows across the 20 machine, the numeral keys being in the rear row. Each of the printing keys is connected by a link 29 with a sub-lever 30 which in turn is connected by a link 31 with a type bar 32 having types 33 on its free end. In 25 the drawings I have shown only one of these type bars and its connections, as the construction of the machine is well known. All of said type bars are mounted in hangers which are secured to a stationary segment 34.

30 The Wahl adding attachment comprises a stationary frame including a frame plate 35 which is secured by means of brackets 36 to the top plate 3 of the typewriter. The plate or frame piece 35 supports the actuator 37 of 35 the adding attachment, which actuator is of well-known construction and need not be particularly described herein. Said actuator, however, comprises a series of key-operated levers 38 which, through certain mechanism 40 including spirally arranged arms 39 mounted on a rock shaft 40, actuate the master wheel 41, which master wheel is adapted to actuate the adding heads or registers. The levers 38 of the Wahl machine, are operated 45 by links 42 extending to those of the key levers 27 which carry the numeral keys 28 of the typewriter.

50 The computing mechanism includes a carriage consisting of a bar 43 which resembles, in a general way, the carriage bar of the Wahl machine; but I have modified it somewhat as will presently appear. The bar 43 includes a track-way along its under side which is engaged by a roller 44, which roller 55 supports the weight of the carriage at the middle. A second roller 45 engages the rear surface of the carriage at the bottom thereof. In the Wahl machine there is a third roller turning on a vertical pivot and running in 60 a groove in the top of the carriage bar. I have modified this construction, making the groove 46 face downward instead of upward and the roller 47 engaging the flange 48, which flange is a depending instead of 65 an upstanding flange. I also employ an ec-

centric guard 50 to prevent lifting of the bar 43, this guard being similar to the one used in the Wahl machine. It will be understood that the rollers 44, 45 and 47 and the guard 50 are all mounted on the frame piece 70 35 approximately in the fore and aft vertical plane through the master wheel. At its ends the carriage bar 43 is provided with arms 51 which are connected by pin and slot connections 52 with brackets 53 which are 75 secured by screws 54 to the side bars of the typewriter carriage 5.

The general principle of the carriage suspension shown and described, is substantially like that set forth in the patent to 80 Webster No. 968,103, dated August 23, 1910, the principal difference being in the changed location of the roller 48. The computer also includes one or more adding heads 55 which are mounted on the carriage 85 bar 43 in the manner common in the Wahl machine, except as to the form and arrangement of the detent, which will be more particularly described hereinafter. These adding heads 55, as to their internal mechanism, may be substantially identical with those employed in the Wahl machine or as far as my invention is concerned, they may be of any suitable construction.

On each of the adding heads 55 I mount 95 a combined detent and column stop device which I have designated generally by the numeral 56. In the form in which this device is shown in the present instance, it consists essentially of a piece of sheet metal 100 mounted on one face of the adding head by means of shouldered and headed screws 57 and 58. The screw 57 passes loosely through a horizontal slot 60 and the screw 58 passes through an L-shaped slot 61 in the device 105 56, said L-shaped slot having a horizontal branch and a vertical branch running downward from the rear end of said horizontal branch. Said device 56 normally stands in the position shown in Fig. 3, for example, 110 where the screws 57 and 58 are in the middle of the longitudinal slots. Said device is held in this middle position by means of a spring 62 coiled about a pin or screw 63 on the side of the adding head and having 115 two vertical branches under tension toward each other, their motion being limited by a pin 64 projecting from the side of the adding head between said branches. Another pin 65 projecting from the device 56 also 120 lies between the two branches of the spring 62 and the tension of said spring tends to maintain said pin 65 directly above the pin 64, this being the middle position of the member 56. At its front end said member 125 56 has an upstanding arm from which a key 66 is bent off. Said device has a rearwardly extending arm 67 which, when the adding head is mounted on the carriage 43, lies in and projects through one of the series of 130

slots 68 cut in the uppermost flange of said carriage and situated a letter space distance apart as shown in Fig. 2. The construction is such that when the device 56 stands in its normal middle position shown in Fig. 3, the arm 67 projects a short distance back of the carriage bar 43; but the said device can be pushed back to a rear position shown in Fig. 4 where the arm 67 projects a greater distance toward the rear from the bar 43. By pulling forward on the key 66 the device 56 can be moved to the position shown in Fig. 6, that is to say, it can be pulled forward of its middle position and then tilted up about the pin 57 as a center, the rear end of the member 56 being allowed to move upward by the vertical part of the angled slot 61. When the device 56 is moved to this position the arm 67 thereof is entirely free of the slot 68 in the bar 43 and the adding head is free to be slid along said bar and to be, if desired, entirely removed from the bar. When said adding head is adjusted along the bar to whatever position is desired, it is retained in that position by the device 56 moving down to the position shown in Fig. 3 with the arm 67 in one of the slots 68.

I utilize the arm 67 of the device 56 as a column stop to arrest the computer carriage and with it the typewriter carriage at any desired position in the adding column. To this end I have provided a series of denominational stops 70 for coöperation with these arms 67. Said denominational stops consist of angled levers of the form shown in the drawings, said levers being pivoted on a rod 71 mounted in a frame 72, which frame at its upper part, has mounted thereon in a guide plate 73, said guide plate having slots situated a letter space distance apart for guiding the stops 70. For a purpose which will presently appear, the frame 72 is pivoted on a horizontal pivot 74 to the frame plate 35 which supports the actuator and carriage of the computer. Each of the stops 70 has a rearwardly directed arm 75 adapted to be pushed up by a push bar 76 in order to throw the upper end of the stop 70 into the path of the column stop 67. There is a series of these push bars 76 suitably guided in slots in the frame piece 35 and secured in position by a guard plate 77. The stop 70 may be provided with any suitable restoring springs 78. Each of the push bars 76 is pivoted at its lower end at 79 to a horizontal lever arm 80 that is pivoted on a cross bar 81, which, as here shown, is mounted in brackets 82 (Fig. 1) mounted on the base part 1 of the typewriter. Each of the arms 80 is connected by a diagonal bar 83 with another arm 84 (Figs. 1 and 2) which is also pivoted on the rod 81. Each of said arms 84 has in the forward end thereof a cam slot 85 into which a pin 86

projects from the side of a lever 87, which lever is pivoted on a cross bar 88 mounted in the base of the typewriter. The levers 87 are levers of the first order and their depending arms have pivoted thereto the rear ends of push bars 90 which at their forward ends are guided in a frame 91 and carry denominational tabulator keys 92. The levers 87 are also controlled by returning springs 93 each connected at one end to one of said levers and at the other end to a frame plate 94 (Fig. 1). The cam slot 85 as shown consists of two dwells, one at each end of the slot and at different elevations, and said dwells connected by an inclined part, the construction being such that when the key 92 is pushed toward the rear the arm 84 is forced upward, rocking the lever consisting of the parts 84, 83 and 80 upward and pushing upward therefore on the bar 76 and rocking the stop 70 into the path of the stops 67.

The bars 80, as shown in Fig. 2, are spaced a distance apart not much greater than a letter space distance, whereas the arms 84 are spaced apart according to the spacing of the tabulator keys 92. The diagonal bars 83 are situated above the lever arms 84 and 80, as shown in Fig. 1, and they connect the two arms in such a way that when one of them is rocked about the shaft 81 the other one is rocked also. As shown in Fig. 2 the outermost ones of these bars 83 extend clear across two intermediate arms 84 so that the arms 80 are grouped close together in the middle of the machine and still are operatively connected with their respective arms 84.

In order to release the carriage when one of the tabulator keys 92 is operated, a universal bar 95 is provided, said universal bar lying behind the lower arms of the levers 87 and being supported by vertical arms 96 pivoted on the rod 88, the construction being such that when any of the keys 92 is operated the universal bar 95 is swung toward the rear of the machine. This universal bar and the levers 87, at least as far as the lower arms of said levers are concerned, are similar to the corresponding parts now employed in the Wahl-Remington machine, said universal bar having an arm 97 which is connected by a link 98 with an arm 100 rigidly mounted on and depending from a transverse rock shaft 101 pivoted in the rear of the base of the typewriter. Said rock shaft also has mounted thereon another arm 102 of the angled form shown in Fig. 1, which arm 102 is connected by a pull link 103 with a lever 104 of the first order, which lever is pivoted at 105 to a bracket 106 mounted on the top plate 3 of the machine. The forward end of the lever 104 is bent off to form a shoe that lies beneath the feed rack 12 of the typewriter 139

carriage. The construction is such that whenever the universal bar 95 is moved toward the rear, the lever 104 is rocked and lifts the feed rack 12 out of engagement with the pinion 14 and thus releases the carriage from the control of the escapement mechanism. When the key 92 is released the parts just described are restored to normal position by means of a restoring spring 107 connected at one end to the arm 100 and at the other end to a frame plate 108.

The operation of the parts when the member 56 stands in its normal, middle position shown in Fig. 1, will be understood from the above description. When any of the tabulator keys 92 is operated, the corresponding one of the denominational stops 70 is moved forward as shown in Fig. 3 and the carriage is released and run down until it is arrested by one of the stops 67, encountering the projected stop 70. As all of said stops 67 project toward the rear to the same distance, the stop 70 will arrest the first stop 67 that reaches it. I have provided means for selecting among the columns, that is to say, I have provided means whereby a key 92 can be operated and the typewriter and computer carriages moved freely until the stop 67 of a selected one of the adding heads has reached the projected stop 70, other adding heads passing freely by said stop 70. It is for this reason that the member 56 is made movable toward the rear to the position shown in Fig. 4. It will be noted that the spring 62 tends to restore this member to its Fig. 3 position. I prefer to provide means for holding the member 56 in its Fig. 4 position temporarily. Said means consists of a spring plate or bar 110 riveted at 111 to the member 56 and projecting toward the rear above and parallel to the arm 67. As shown in Fig. 2 the detent 110 is thicker at its rear end than it is throughout the remainder of its length. It is so constructed that when the member 56 is moved back to the rear position shown in Fig. 4, this plate 110 springs to the left, its thickened rear end hooking in behind a tooth of the bar 43. The construction is also such that when the carriage moves to the left until the projected stop 67 is arrested by the projected one of the stops 70, that said stop 70 unlatches the plate 110, thus leaving the member 56 free to be moved toward the front of the machine to its normal position by the spring 62.

When the stop 67 is pushed toward the rear as shown in Fig. 4, it moves toward the rear a long universal bar 112, which universal bar has vertical arms 113 which are pivoted at 114 (Fig. 2) to the brackets 53 in such a way that the universal bar is capable of motion in a front and back direction. As shown in Figs. 3 and 4, the universal bar

112 stands just in front of and in contact with the frame 72 in which the stops 70 are mounted. The construction is such that when the bar 112 is moved toward the rear as shown in Fig. 4, it also swings the frame 72 toward the rear, thus moving the stops 70 to the rear of their normal position shown in Fig. 1. If now one of said stops 70 be operated, by operating the corresponding key 92, it will be projected in front of its companions, and in position to engage the rearwardly moved one of the column stops 67 but not far enough to engage those column stops 67 that remain in the Fig. 3 position. The result of this operation will be that when the carriage is released it will move toward the left and any adding heads whose stops 67 have not been moved toward the rear will pass the projected stop 70 freely and said projected stop will arrest only the adding head whose stop 67 has been pushed to the rear as shown in Fig. 4. It will thus be seen that if no stop 67 is pushed to the rear and all of said stops are left in their normal, middle positions, then the tabulator operates like any ordinary denominational tabulator in this respect, that when one of the denominational stops is operated it will arrest the first column stop that reaches it; but if one of said column stops has been moved to its rear position, then the projected denominational stop is rendered incapable of arresting any other column stop than the one that has been thus moved. When said column stop is arrested the engagement of the stop 70 with the latch 110 will release said stop and permit it to move back to its normal position. This motion, however, will not free it from the stop 70 because if it thus moves back to normal position while the two stops are in engagement, the universal bar 112 and the frame 72, and with them the denominational stop 70, will all move forward also, being impelled in this movement by a spring 115 best shown in Fig. 8, which spring is secured by a screw 116 to the stationary part of the framework and presses against the frame 72, pressing said frame toward the front of the machine.

As it may be desired to arrest the carriage sometimes in positions that do not correspond with adding columns, I have provided special column stops that are not mounted on adding heads but are mounted on the computer carriage preferably in the same general manner as the adding heads. Such a device is shown in Figs. 2 and 7 where the parts 56 and those associated therewith are substantially like the corresponding parts mounted on the adding heads and are designated by the same reference numerals. A plate 117 is provided, said plate being shaped somewhat like one of the side plates of an adding head; that is to say, it is provided with the side dove-tail ar-

angement for securing it to the bar 43 and it is also provided with the screws 57, 58 and 63 and pin 64. This plate is also formed with two branches 118 one at the upper and the other at the lower edge thereof, said branches being bent off horizontally toward the right as shown in Fig. 2 and each of said branches having an arm 120 bent off therefrom toward the rear, these two arms 120 being dove-tailed on to the bar 43 so as to give the plate 117 a sufficiently rigid mounting on said bar. The stop bar 67 projects through the slots 68 in the same manner as the corresponding parts mounted on the adding head. It will, of course, be understood that the machine can be equipped entirely with these special column stops if desired without any adding heads at all. It will thus be seen that my improvements 20 are applicable to typewriting machines in which there is no computer and also to computing machines in which there is no typewriter.

When there are several adding heads and detached column stops in the machine it may sometimes be desired to make a number of entries in some one or two of the columns to the exclusion of the remaining columns, and this work can be done more conveniently if one or more of the column stops can be pushed in to its operated position and be held there so as not to be released by the denominational stop. This can be provided for in a variety of ways, but I prefer to 30 mount adjacent to each of the column stops a hand operated detent that can be moved into engagement with the associated column stop if desired. In the present instance, I have shown a latch 121 pivoted at 122 to 40 the top of the adding head or to an ear 123 of the frame 117. The latch 121 has a nose 124 which is adapted to be moved in behind the shoulder 125, Fig. 3, of the part 56. The latch 121 may be provided with a 45 finger piece 126 and a stop pin 127 may be so placed as to limit the motion of the latch toward the right.

It will be perceived that each of the stops 67 is adapted to be adjusted or shifted at 50 will and independently of its support and of the other stops 67 so that it can occupy either a normal position or a shifted position, and that the key-actuated coöperating stops can engage it in both of said positions; that said coöperating stops are adapted to engage with all of said stops 67 when the latter are in like positions, but are adapted to engage only with the shifted stop when any one of said stops 67 is in 55 shifted position; that the engaging face of each of the column stops is adapted to travel in either of two parallel lines and the coöperating stop can engage said column stop whether its engaging face is 60 traveling in one or the other of said lines;

that said coöperating stops are movable to terminate at either of two different positions to coöperate with a stop 67 traveling in either of two parallel lines; and that means are provided for simultaneously 7 shifting or adjusting said coöperating stops and a selected one of the stops 67.

If a number of items in succession are to be written in some one column to the exclusion of other columns, or if for any 75 other reason it is desired to dispense with the automatic release of an operated column stop the column stop can be pushed toward the rear and the latch just described can be moved to the left to hold the column stop in its operated position until said latch is released by hand. When the latch 121 is in use the release of the 80 detent 110 by the denominational stop does not permit the column stop to return to 85 normal position.

Various changes can be made without departing from my invention.

What I claim as new and desire to secure by Letters Patent, is:—

1. In tabulating mechanism, the combination with a traveling carriage, of one or more column stops each adjustable with relation to the travel of said carriage, means for operating said column stops to 95 select columns, means for locking the operated column stop in operated position, and one or more key-operated coöperating stops acting when said stops arrest the carriage to release locking means. 100

2. In tabulating mechanism, the combination of a series of column stops, a series of coöperating denominational stops, means for operating said denominational stops, said denominational stops when operated 105 being adapted to engage any one of said column stops, means for moving any one of said column stops to an operated position, and means operated by said moving means for preventing coöperation between said 110 denominational stops and the unoperated column stops.

3. In tabulating mechanism, the combination of a series of column stops, a series of coöperating denominational stops, means 115 for operating said denominational stops, said denominational stops when operated being adapted to engage any one of said column stops, means for moving any one of said column stops to an operated position, and means operated by said column stops for moving said denominational stops so that when one of said denominational stops is operated it will coöperate only 120 with the operated one of said column stops. 125

4. In tabulating mechanism, the combination of a series of denominational stops, a movable support for said denominational stops, means for operating said stops in either of two positions of said support, a 130

- series of column stops, means for operating said column stops, and means whereby an operation of a column stop moves said support, the construction being such that when said support is in one position and a denominational stop is operated, said denominational stop is adapted to coöperate with any of said column stops but when said support is in the other position the operated denominational stop is adapted to coact only with the operated column stop.
5. In tabulating mechanism, the combination of a series of independently operable denominational stops, a series of independently operable column stops for coöperation with said denominational stops, and means operated by an operation of one of said column stops for modifying the action of said denominational stops so that when the 10 column stops are in normal position and a denominational stop is operated, said denominational stop is adapted to coöperate with any one of said column stops, whereas when one of said column stops is operated 15 and a denominational stop is also operated, said denominational stop is adapted to coact only with the operated one of said column stops.
6. In tabulating mechanism, the combination of a traveling carriage, stops mounted on said carriage, relatively stationary co-operating stops, means for moving the carriage stops toward said relatively stationary stops, and a universal bar mounted on 20 the stationary framework and arranged to be operated by said carriage stops.
7. In tabulating mechanism, the combination of a traveling carriage, one or more column stops adjustable lengthwise of said 25 carriage, means for operating any one of said column stops, one or more relatively stationary coöperating stops, and a universal bar mounted on the stationary framework and arranged to be operated by said column stop or stops.
8. In tabulating mechanism, the combination of a series of adjustable column stops, a series of denominational stops, means for moving any one of said column 30 stops to an operative position, a universal bar arranged to be operated by any of said column stops, and means operated by said universal bar for shifting the whole series of denominational stops.
9. In tabulating mechanism, the combination of a traveling carriage, one or more column stops mounted on said carriage and adjustable lengthwise thereof, means for moving any one of said column stops to 35 an operative position, a coöperating stop, a universal bar operated by any of said column stops, means whereby said universal bar shifts said coöperating stop, and means for operating said coöperating stop.
10. In tabulating mechanism, the combi-

nation of a traveling carriage, one or more column stops mounted on said carriage and adjustable lengthwise thereof, a relatively stationary set of denominational stops, means for operating any of said column 70 stops, a universal bar arranged to be operated by said column stops, means whereby said universal bar shifts said set of denominational stops, means for operating said denominational stops, and a carriage release 75 device operated by an operation of one of said stops.

11. In tabulating mechanism, the combination of a traveling carriage, one or more column stops each adjustable with relation 80 to the travel of said carriage, means for operating said column stops to select columns, means for locking the operated column stop in operated position, and a coöperating stop acting when said stops arrest the carriage 85 to release said locking means.

12. In tabulating mechanism, the combination of a series of column stops, each independently adjustable to different letter space positions, a coöperating stop, means 90 for operating said coöperating stop, and means for setting said column stops individually in two positions in one of which said coöperating stop acts on all of said column stops alike and in the other of which 95 said coöperating stop acts on said column stops selectively.

13. In tabulating mechanism, the combination of a series of column stops, each independently adjustable to different letter space positions, a coöperating stop, means 100 for operating said coöperating stop, means for setting said column stops in two positions in one of which said coöperating stop acts on all of said column stops alike and in the other of which said coöperating stop acts on said column stops selectively, and means for shifting said coöperating stop when one of said column stops is set to selective position.

14. In tabulating mechanism, the combination of a set of tabulator stops, a co-operative stop which, when operated, is capable of engaging any one of said tabulator stops, said tabulator stops being independently movable toward said coöperative stop, and means whereby such movement of a tabulator stop renders the co-operative stop coöperable only with the moved tabulator stop.

15. In tabulating mechanism, the combination of a set of tabulator stops, a set of coöperative stops each of which when operated is capable of engaging any one of said tabulator stops, said tabulator stops being independently movable toward said coöperative stops, and means whereby such movement of one of said tabulator stops renders said coöperative stops coöperable 125 only with said moved tabulator stop.

16. In tabulating mechanism, the combination of a set of column stops, a set of co-operative denominational stops, said denominational stops, when operated, being capable of engaging any one of said column stops, means for shifting said column stops independently of each other toward said denominational stops, and means whereby the shifting of one of said column stops toward the denominational stops renders said denominational stops inoperative on all the column stops except the one shifted.

17. In tabulating mechanism, the combination of a set of column stops each independently operable, a support for said stops, a co-operative stop, said co-operative stop being, when operated, normally capable of engaging any one of said column stops, a separate key for each column stop for shifting it on its support toward the co-operative stop, and means whereby such shifting of a column stop renders said co-operative stop incapable of engaging the other column stops.

18. In tabulating mechanism, the combination of a set of column stops, a set of co-operating denominational stops, said column stops normally having their contact faces in line and said denominational stops being normally capable, when operated, of engaging any of said column stops, means for shifting one of said column stops out of line, and means operated by said shifting means for rendering the denominational stops capable of contacting only with said shifted column stop.

19. In tabulating mechanism, the combination of a set of tabulator stops, a co-operative stop, said tabulator stops being movable into co-operation with said co-operative stop, means for locking any one of said tabulator stops in its operated position, means for automatically releasing said lock by the contact of the stops, and means for preventing the release of the stop.

20. In tabulator mechanism, the combination of a series of operatable stops, a co-operating stop, means for holding any one of the said operatable stops in its operated position, said means being automatically releasable by said co-operating stop, and hand operated means for holding said operatable stop in its operated position, the last recited means being incapable of release by said co-operating stop.

21. In tabulator mechanism, the combination of a series of key operated stops, springs for restoring said stops to normal position, and a hand operated detent for use when desired, to hold one of said stops in operated position against the action of its restoring spring.

22. In tabulating mechanism, the combination of a carriage, a slotted bar parallel

with the line of travel of said carriage, a column stop adjustable along said bar and retained in adjusted position by the slots in said bar, a co-operating stop, means for moving said column stop to an operated position, and a detent for holding said column stop in such position, said detent being releasable by said co-operating stop.

23. In tabulating mechanism, the combination of a series of denominational stops, a set of column stops normally in position to be engaged by any operated one of said denominational stops, means for moving one of said column stops to a shifted position, means operated by said shifting means for rendering said denominational stops incapable of contacting with any but the shifted stop, and a detent for said shifted stop arranged to be released by a denominational stop.

24. In tabulating mechanism, the combination of a series of denominational stops each having the form of an angled lever, a shiftable frame in which said denominational stops are mounted, denominational keys and connections to said stops, said connections including bars arranged to co-operate with one of the arms of each of said stops in either position of said shifted frame, column stops, and column selecting means including means for shifting said frame.

25. In tabulating mechanism, the combination of a series of denominational stops, a series of bars for operating said stops, a series of levers for operating said bars, a series of keys for operating said levers, each of said levers having two arms, one connected with one of said bars and the other connected with one of said keys, and the former arms connected with the latter by cross-over branches whereby the key operated arms are spaced farther apart than the bar-operating arms, the key connections including pin and cam slot connections to said key operated arms.

26. The combination of a carriage, a stop bar, column stops carried by said stop bar, and a key carried by the carriage for moving one of said column stops individually on the stop bar.

27. The combination of a carriage, a stop bar, column stops carried by said stop bar, denominational stops, and a key for moving one of said column stops individually toward said denominational stops, said denominational stops being capable of co-operating with said column stop both in its normal and its moved positions.

28. The combination of a traveling carriage, a series of supports adjustable lengthwise of said carriage, a series of column stops one movably mounted on each of said supports, each of said stops acting as a detent to retain its said support in adjusted position, relatively stationary co-operating

stops, means for moving any of said carriage stops toward said relatively stationary stops, a universal bar arranged to be operated by said carriage stops, and means operated by 5 said universal bar for changing the relation of said relatively stationary stops to said carriage stops.

29. The combination of a carriage comprising a part having a series of open ended 10 slots therein; a support adjustable along said carriage; a combined detent and column stop mounted on said support and adapted to be moved into one of said slots to retain said support in adjusted position, said combined detent and stop being mounted on 15 said support for a swinging motion to move it into and out of said slot and said stop being also provided with a key whereby it can be given a sliding motion from a normal 20 position to an operated position; and a non-traveling coöperating stop.

30. In a tabulating mechanism, the combination of a series of column stops, a key 25 controlled stop which in the normal positions of the parts is adapted when actuated to engage each one of the column stops, and means for shifting the position of any selected one of said column stops, and for causing the key controlled stop when actuated, after such shifting operation, to engage with only the predetermined or selected and shifted column stop.

31. In a tabulating mechanism, the combination of a stop adapted to occupy a normal and a shifted position, and a coöperating key actuated stop adapted to engage with the first mentioned stop in both of its 35 said positions.

32. In a tabulating mechanism, the combination of a series of stops each independently adapted to occupy either of two positions and a coöperating key actuated stop adapted to engage with all of said first mentioned stops when they are all in like 40 positions, and also adapted to engage only with any of said stops which may be moved to the other position which it is capable of occupying.

33. In a tabulating mechanism, the combination of a series of stops each independently adapted to occupy two different positions, and a series of coöperating key actuated stops adapted each to engage each of 45 the first mentioned stops in both of the two 50 positions which it is adapted to occupy.

34. In a tabulating mechanism, the combination of a traveling column stop independently adjustable on its support, so that 55 its engaging face is adapted to travel in either of two parallel lines, and a coöperating stop, adapted to engage said stop whether its engaging face be traveling in one or the other of said lines.

35. In a tabulating mechanism, the combination of a series of column stops adjust- 65 able independently and at will relatively to each other and to their support so that their engaging faces may be made to travel in either of two parallel lines, and a co- 70 operating stop adapted to engage said column stops whether their engaging faces be adjusted to travel in one of said lines or the other.

36. In a tabulating mechanism, the combination of a series of traveling column 75 stops adjustable relatively to each other at right-angles to their path of travel so that the engaging face of each may be made to travel in either of two lines, and a series 80 of coöperating denominational stops each adapted to coöperate with said column stops at one time in one of said lines and at another time in the other of said lines, according to adjustment.

37. In a tabulating mechanism, the combination of a traveling stop adjustable at right-angles to its path of travel so that its 85 engaging face may be made to travel in either of two parallel lines, and a coöperating stop adjustable so that its engaging face 90 is movable to terminate at either of two different positions relative to said first named stop.

38. In a tabulating mechanism, the combination of a series of traveling stops each 95 independently adjustable at right-angles to its path of travel so that its engaging face may be made to travel in either of two parallel lines, and a coöperating stop adjustable so that its engaging face is movable to 100 terminate at either of two different positions relative to said first mentioned stops.

39. In a tabulating mechanism, the combination of a column stop having two different working positions, a coöperating stop 105 capable of engaging said column stop in both said positions, and means for shifting or adjusting said column stop from one of said positions to the other and for simultaneously shifting said coöperating stop. 110

40. In a tabulating mechanism, the combination of a series of column stops, a coöperating stop, and means for simultaneously shifting or adjusting said coöperating stop and a selected one of said column 115 stops independently of the remaining column stops.

41. In a tabulating mechanism, the combination of a series of column stops, a coöperating series of denominational stops, and means for simultaneously shifting or 120 adjusting said series of denominational stops and a selected one of said column stops independently of the remaining column stops.

42. In a tabulating mechanism, the combination of a series of column stops, a coöperating stop capable of engagement with

each of said column stops in one position for column-to-column tabulation, and means for causing said coöperating stop to engage the same engaging face of a selected one of said 5 column stops in another position for column selecting tabulation.

Signed at the borough of Manhattan, city

of New York, in the county of New York, and State of New York, this 31st day of Jan. A. D. 1912.

JOHN WALDHEIM.
